ELECTRICAL WIRE CONNECTOR WITH
INSULATION PIERCING MEANS

Henry J. Schroeder, Chicago, Ill.

Application April 20, 1946, Serial No. 663,683

1 Claim. (Cl. 174—84)

1

This invention relates to improvements in electrical wire connectors for securing a wire therein or for firmly joining a plurality of wires together in physical and electrical contact, and refers particularly to connectors adapted to form electrical contact with or between insulated wires.

One of the objects of the invention is to provide a connector which can be manually and quickly applied without the use of tools and does not require removal or stripping of the insulation covering of the connected portions of insulated wires when such wires are used.

Another object resides in the provision of a versatile type of connecting device for use on either insulated, partially insulated, or bare metallic wires of either the solid or stranded type.

A further object is to provide a low cost means for effecting the electrical connection of wires which does not require the twisting or soldering of the wires or connector or further insulation of said connection.

Briefly described, my invention comprises a metallic clip member having one or more sets of serrations or teeth, or continuous insulation-cutting edges which securely grip the wires to be connected adjacent their ends, either piercing the insulation or contacting the bare metallic surfaces of the wire; the clip thus gripping the wire or wires is insertable within a sleeve or cap having converging or inclined inner walls which exert a constricting force upon the clip to firmly clamp the juxtaposed teeth or contacting edges upon the wire, means being provided for anchoring the clip within the cap to hold said clip in wire-clamping position.

Other objects and advantages of my invention will be apparent from the accompanying drawing and following detailed description.

In the drawing,

Fig. 1 is a sectional elevational view of a preferred form of my invention.

Fig. 2 is a transverse sectional view taken on the line 2—2 of Fig. 1.

Fig. 3 is a perspective view of the connector employed with the form of my invention illustrated in Figs. 1 and 2.

Fig. 4 is a longitudinal sectional elevation of a modification of my invention.

Fig. 5 is a transverse sectional view taken on the line 5—5 of Fig. 4.

Fig. 6 is a perspective view of the conductor employed with the form of my invention shown in Figs. 4 and 5.

Fig. 7 is a longitudinal sectional elevation of another modification of my invention.

2

Fig. 8 is a transverse sectional view taken on the line 8—8 of Fig. 7.

Fig. 9 is a perspective view of the connector employed with the form of my invention shown in Figs. 7 and 8.

Fig. 10 is a longitudinal sectional elevation of another form of my invention.

Fig. 11 is a similar view showing a slight modification of the form of my invention illustrated in Fig. 10.

Fig. 12 is a similar view showing a further modification.

Fig. 13 is a longitudinal sectional view of a composite cap which may be employed in conjunction with my invention.

Referring in detail to the drawing, 1 indicates an electrical connector which comprises a cap 2 and a connecting member or clip 3. The clip 3 is preferably constructed of resilient metal such as hardened copper, brass or the like, and the same is bent to form two opposed plates 4 and 5. Each of the plates 4 and 5 terminates in juxtaposed teeth or serrations 6, which, as will be hereinafter more fully described, are adapted to grip or bite into two or more electrical conductors.

In employing the invention illustrated in Figs. 1, 2 and 3, the ends of a pair of insulated conductors 7 are inserted between the teeth 6. The two plates 4 and 5 are then manually urged towards each other to cause the teeth to penetrate the insulation upon the conductors 7 and also to penetrate the body of the conductors themselves thereby making electrical connection through the clip 3 between the two conductors. With the ends of the conductors 7 held between the teeth 6 of the clip 3, the clip is inserted into the open mouth of the cap 2. The cap 2 is constructed of an insulating material such as hard rubber, Bakelite or other synthetic resinous material which has both strength and properties of high electrical resistance. The cap 2, in the form of my invention illustrated in Figs. 1 and 2, is of hollow form having a substantially square sectioned open mouth portion, and having tapered walls which terminate in an apex 8, the walls of the cap forming a dihedral angle.

When the clip 3 holding the conductors 7 is inserted into the cap, the opposed plates 4 and 5 of the cap are brought into contact with the inclined walls of the cap and thus a force is established tending to move both sets of teeth 6 toward each other, thereby firmly gripping the conductors 7.

The plates 4 and 5 are provided with transverse projecting beads 9 which are disposed adjacent

those ends of the plates which carry the teeth 6. The opposed inner tapered walls of the cap 2 are provided with transverse grooves 10 into which the beads 9 register. Consequently, when the clip 3 is inserted into the body of the cap 2, said clip by means of the engagement of the beads 9 in the grooves 10 is securely locked within the cap. By virtue of the fact that the cap 2 is of insulating material, no danger exists of injury being caused by contact with the metallic clip which electrically bridges the two conductors 1.

Referring particularly to Figs. 4, 5 and 6, another form of my invention is shown. In this form of my invention a cap 11 is constructed of material similar to that of the cap 2 is adapted to carry a clip 12. The cap 11 is hollow and is of circular transverse section, said cap having tapered walls of conical form. The clip 12 comprises a metallic member, constructed of a material similar to the clip 3, and comprises two opposed plates 13 and 14 which are connected by a bend 15. Each of the plates 13 and 14, in form, comprise a portion of the surface of a cone and said plates terminate at their free ends in juxtaposed teeth 16.

In utilizing this form of my invention, a pair of conductors 17 may be connected electrically by inserting their ends between the juxtaposed teeth 16. The teeth 16 are so formed that a space is provided at the central portion of the line of teeth whereby the conductors may be inserted between the teeth in superimposed relationship, as shown best in Figs. 4 and 5. With the conductor ends in position between the teeth 16, the plates 13 and 14 are manually squeezed together so as to cause the central tooth projected from each plate to extend through the insulation upon the conductors and into the metallic wires themselves, thereby effecting electrical connection between the two wires. A shoulder 18 is formed at the base of the teeth 16 and similarly a shoulder 19 is provided on the interior portion of the cap 11. With the conductors 17 firmly gripped between the teeth 16, the clip 12 is inserted into the hollow cap 11 and by contact of the conical walls of the cap 11 with the plates 13 and 14, the teeth are firmly urged into the body of the conductors. When the clip has been moved to its limiting position within the cap, the shoulders 18 of the clip engage the shoulders 19 on the interior walls of the cap, thereby retaining the clip firmly in position within the cap.

Referring particularly to Figs. 7, 8 and 9, a further modification of my invention is shown and comprises a cap 20 and a clip 21. The cap 20 is of hollow construction and has conically tapered walls similar to the cap 11. The cap 20 is also of circular transverse section and may be constructed of a material similar to that comprising the cap 2.

The clip 21 is of a material similar to the clip 3 and comprises two tapered flat plates 22 and 23 which are joined by a U-bend 24. In this form of clip one set of teeth 25 project from the plate 22 whereas the opposite plate 23 carries no teeth. Each plate 22 and 23 is provided with a struck-up button 26 which, as will be hereinafter more fully described, is adapted to hold the clip within the cap 20.

In utilizing this form of my invention, the ends of two conductors 27 are inserted between the teeth 25 and the forward end of the plate 23, and a force is exerted squeezing said plates toward each other whereby the teeth 25 penetrate the insulation of the conductors and also pene-

trate the body of the wires within said insulation, thereby making electrical connection between the wires through said clip. The clip 21 is then inserted into the cap 20 and the tapered walls of the cap function to urge the teeth 25 toward the free end of the plate 23 thereby securely engaging or clamping the conductors 27. When the clip 21 has been moved to its limiting position within the cap 20, the buttons 26 engage in indentations 28 provided in the interior surfaces of the walls comprising the cap 20. In addition, a shoulder 29 is formed at the base of the teeth 25 which engages a shoulder 30 formed in the interior surface of the cap 20.

Referring particularly to Fig. 10, a connector 31 is shown which is adapted to make electrical connection between two abutting conductors 32 and 33. The connector 31 comprises a cap portion 34 which is provided with a pair of oppositely inclined conical walls.

The cap 31 is adapted to carry a pair of similar clips 35 and 36 which are of substantially the same construction as the clip 12. Each of the clips 35 and 36 are provided with pairs of juxtaposed teeth 37 and 38 respectively, and each of said clips are provided with struck-up portions 39 and 40 respectively.

In utilizing this form of my invention the end of one of the conductors, conductor 32 for instance, is inserted between the teeth 37 before the clip 35 has been inserted within the cap 34. The clip is then squeezed in order to cause the teeth 37 to penetrate the insulation and the metal of the conductor 32 as has been hereinbefore described in conjunction with the other forms of my invention. The clip 35 is then inserted in the cap 34 until the struck-up buttons 39 engage in recesses provided in the interior of the cap 34. The clip 36 gripping the conductor 33 is also inserted in the cap 34 and the U-bent portions are brought into contact with each other as shown best at 41 to provide electrical connection between the metallic wires and the conductors 32 and 33 through the clips 35 and 36.

Referring particularly to Fig. 11, a connector 42 similar to the connector 31 is illustrated. The connector 42 comprises a cap portion 43 and clips 44 and 45. The clips 44 and 45 are of a construction similar to the clips 35 and 36, and the cap 42 is substantially similar to the cap 34. However, in this form of my invention a metallic block 46 positioned intermediate the cap 43 makes electrical connection between the apices of the clips 44 and 45. Otherwise, the form of my invention shown in Fig. 11 is substantially similar to the connector 31 shown in Fig. 10.

Referring particularly to Fig. 12, another modification of my invention is shown wherein a clip 47 of construction similar to the clips 35, 36, 44 and 45 is insertable within a cap 48. The connector 49 comprising the clip 47 and cap 48 is adapted to be employed as a male plug. In this form of my invention, teeth 49 of the clip 47 penetrate the insulation and the metal of the conductor 50, and the clip makes electrical connection with a metallic block 51 carried by the cap 48, said block being positioned in electrical contacting relationship with the apex of the clip 47.

A metallic finger 52 may comprise a portion of the block 51 or may be electrically connected thereto, and projects from the cap whereby said finger may be brought into engagement with a suitable female receptacle (not shown) to effect

electrical contact between the conductor 50 and the circuit comprising the female receptacle.

Referring particularly to Fig. 13, a cap 53 comprises an inner metallic lining member 54 and an exterior insulating portion 55. The cap 53 is similar in construction to the cap 2 hereinbefore described in conjunction with the form of my invention illustrated in Figs. 1, 2 and 3.

By the provision of the metallic lining 54, the cap 53 is strengthened and yet having an insulated outer surface 55, the electrical connections made by a clip such as the clip 3 are insulated from the outside of the cap. It is to be understood, of course, that the cap construction illustrated in Fig. 13 may be employed in any of the forms of my invention hereinbefore described, the only distinction being that a metallic reinforcing inner lining is provided for the cap.

The device comprising my invention may be used advantageously to make electrical connections of wires in the fabrication of various electrical devices such as electrical motors, generators, portable power plants, lighting fixtures, lamps, fans, blowers, air exhaust units, shavers, hair dryers, heaters, heating pads, stoves, food mixers, toasters, coffee makers, waffle irons, grinders, washing machines, switches, electric irons and a host of other types of electrical devices. In addition, my invention may also be employed in the splicing of house and power wiring. It can readily be seen that time, labor and costs can be decreased through the elimination of manual operations such as skinning of wire insulation, twisting of wires, soldering, taping, use of special tools, screwing of caps, and other manual operations heretofore necessary in making electrical connections.

Although my invention has been described in conjunction with clips 3, 12, 21, 35, 36, 44, 45 and 47 which have penetrating teeth, it is to be understood that a continuous knife edge can be used instead of the teeth. In this form of my invention, however, care must be exercised so as not to exert too much pressure upon the clip and thus sever the wire or wires connected by said clip. In addition, although my invention has been described in conjunction with unskinned wire, it is to be understood that the advantages thereof are also applicable to skinned or bare wires.

Broadly my invention is directed to a cantilever type metal clip having conductor-engaging members which bite or grip the conductor insertable

therein at substantially right angles to the axis of the conductor, said clip being housed in an insulating shell. By gripping the conductors in this fashion, the engaging edges or teeth of the clip are rigid with regard to their relationship to the conductor and said edges or teeth can be forced or driven into penetrating contact with the conductors. In other words no spring or resiliency is contemplated in the conductor-biting edges or teeth, although the remaining portion of the clip may have resilient characteristics.

I claim as my invention:

An electrical connector comprising a hollow cap open at both ends and having oppositely extending sets of divergent walls, said walls being substantially symmetrical about the longitudinal axis of the cap, a pair of metal clips each having opposite convergent sides substantially conforming in convergence with the convergent walls of said cap, the metal sides of each clip being connected by a U-bend at one end of each clip, said clips being insertable in said cap with the convergent sides of each clip in contact with portions of the convergent walls of said cap, conductor engaging means carried by the face ends of the sides of each clip and disposed at substantially right angles to said longitudinal axis of said cap to make penetrating electrical engagement with conductors insertable in said clips along substantially the longitudinal axis thereof, and means for holding said clips in said cap in electrical contact with each other.

HENRY J. SCHROEDER.
